DESIGN FOR A CONTAINER CLOSURE

John E. Sharp, New Kensington, Pa., assignor to Aluminum Company of America, Pittsburgh,
Pa., a corporation of Pennsylvania

Application October 19, 1940, Serial No. 95,932

Term of patent 14 years

To all whom it may concern:

Be it known that I, John E. Sharp, a citizen of the United States, residing at New Kensington, in the county of Westmoreland and State of Pennsylvania, have invented a new, original, and ornamental Design for a Container Closure, of which the following is a specification, reference being had to the accompanying drawing, forming a part thereof, in which:

Fig. 1 is a plan view of a container closure illustrative of my new design; and

Fig. 2 is an elevational view of the container closure shown in Fig. 1.

I claim:

The ornamental design for a container closure, substantially as shown.

JOHN E. SHARP.
